US00D632649S

(12) **United States Design Patent**
Scheucher et al.

(10) **Patent No.:** **US D632,649 S**
(45) **Date of Patent:** **** Feb. 15, 2011**

(54) **CORDLESS POWER SUPPLY**

(75) Inventors: **Karl E. Scheucher**, 7136 Eagle Rd.,
Waite Hill Village, OH (US) 44094;
Greg Guyette, Tampa, FL (US)

(73) Assignee: **Karl E. Scheucher**, Waite Hill, OH (US)

(**) Term: **14 Years**

(21) Appl. No.: **29/266,852**

(22) Filed: **Sep. 29, 2006**

(51) **LOC (9) Cl.** **13-02**

(52) **U.S. Cl.** **D13/110**

(58) **Field of Classification Search** **D13/110, D13/101, 102, 103, 107, 108, 118, 119, 123, D13/184, 199; 307/62, 82, 109, 150, 151; 320/104, 107, 111, 112, 113, 115, 132, 134, 320/150; 361/600, 601, 623; 429/96, 97, 429/98, 99, 100, 163, 170, 176**

CLAIM

The ornamental design for a cordless power supply, as shown and described.

DESCRIPTION

FIG. 1 is a front perspective view of a cordless power supply showing our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a front perspective view of a second embodiment of a cordless power supply showing our new design;

FIG. 9 is a left side elevation view thereof;

FIG. 10 is a right side elevation view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a front perspective view of a third embodiment of a cordless power supply showing our new design;

FIG. 16 is a left side elevation view thereof;

FIG. 17 is a right side elevation view thereof;

FIG. 18 is a top plan view thereof;

FIG. 19 is a bottom plan view thereof;

FIG. 20 is a front elevation view thereof;

FIG. 21 is a rear elevation view thereof;

FIG. 22 is a front perspective view of a fourth embodiment of a cordless power supply showing our new design;

FIG. 23 is a left side elevation view thereof;

FIG. 24 is a right side elevation view thereof;

FIG. 25 is a top plan view thereof;

FIG. 26 is a bottom plan view thereof;

FIG. 27 is a front elevation view thereof;

FIG. 28 is a rear elevation view thereof;

FIG. 29 is a front perspective view of a fifth embodiment of a cordless power supply showing our new design;

FIG. 30 is a left side elevation view thereof;

FIG. 31 is a right side elevation view thereof;

FIG. 32 is a top plan view thereof;

FIG. 33 is a bottom plan view thereof;

FIG. 34 is a front elevation view thereof; and,

FIG. 35 is a rear elevation view thereof.

The broken lines shown represent unclaimed subject matter and form no part of the claimed design.
